FIG. 5.

INVENTOR
William M. White
BY
Loyal J. Miller
ATTORNEY

UNITED STATES PATENT OFFICE.

WILLIAM M. WHITE, OF NORMAN, OKLAHOMA.

VAPORIZING SPRAY FOR FRUIT AND VEGETABLE DISPLAY RACKS.

Application filed July 11, 1928. Serial No. 291,953.

My invention relates to improvements in apparatus for forming and controlling water vapor spray for use in connection with racks for displaying and keeping fresh fruits and 5 vegetables exhibited for sale.

This invention is in particular an improvement over my pending application for fruit and vegetable rack and vapor spray, filed June 4, 1928, Serial Number 282,569.

10 The principal objects of this invention are to provide improvements in devices of this character which will produce a very fine spray or mist which will keep articles cool and fresh without soaking them in water; 15 which will very largely prevent the collection of moisture into drops and which will remove such drops as form before the said drops come in contact with the articles on display.

20 The weight of such articles as cabbage, lettuce, peppers and the like is materially increased by the water said articles will absorb. This fact is well known by persons buying such articles by weight and will militate 25 against the ready sale of such articles. My new improvement obviates this difficulty almost entirely.

Other and further objects will be evident hereinafter as the description of the invention progresses.

The invention consists of the novel construction and arrangement of parts hereinafter described, delineated in the accompanying one-sheet drawing, and particularly 35 pointed out in that part of this instrument wherein patentable novelty is claimed for certain of the distinctive and peculiar features of the device. I desire to be understood that the said drawings and specifications are illustrative and not restrictive. 40 Also that within the scope of the appended claim, divers changes in the form, proportions, size and details may be made, without departing from the spirit or sacrificing 45 any of the advantages of the invention.

Like characters of reference designate like parts in all the figures.

In the accompanying drawings Figure 1 is a front elevational view of the device; 50 Fig. 2 is an end elevation; Fig. 3 is a perspective view of the trays; Fig. 4 is a fragmentary perspective view of the shelf; Fig. 5 is an enlarged fragmentary elevational view, partly in section, of the vapor nozzle 55 and co-acting parts, and Fig. 6 is an en-

larged sectional view of a three part union with wire gauze in place.

One embodiment of my invention will be described as follows: The display rack 1 is preferably made of standard rolled metal shapes and has angle iron corner supports 2, lower longitudinal members 3 for supporting baskets 18, lower transverse members 4, upper transverse members 5 and longitudinal members 6 for supporting drain pan 8, 60 diagonals 7 serving to brace the said rack 1. The said drain pan 8 slopes downward and has outlet at 9. Members 10 are intermediate upright supports, 11 is a solid upright sheet metal end deflector and supporting 70 means enclosed in angle iron frame 12, the turned back metal from scored openings 13 serve as spacing stops for trays 21 positioned adjacent said ends 11. The longitudinal angle members 14 support wire mesh shelf 75 15 enclosed in metal frame 16 above said drain pan 8 and intermediate solid sheet metal top shelf 17. Metal frame wire mesh baskets 18 having shallow back ends 19 and deep front ends 20 are suited for displaying 80 such bulky articles as potatoes, apples, oranges and the like. The said baskets 18 rest on frame members 3 and are tilted forward so that their contents down to the last article will always roll or slide forward to 85 the deep front end 20 where said articles are visible and within reach. The metal frame wire mesh trays 21 are adapted for positioning in and above pan 8, the front ends 22 are shallow and back ends 23 are deep so 90 that such articles as lettuce, celery, radishes and the like may be piled high at the backs of said trays along the longitudinal center of rack 1 where said articles will be thoroughly enveloped in the cool humidified atmosphere from the vapor spray. In order that said spray may reach and surround each of said trays 21, supporting metal straps 24 having raised feet 25 formed on the ends thereof position the trays above pan 8. Said feet 25 extend slightly beyond the sides of 95 said trays so that when feet of adjacent trays are in contact a space 26 is provided between the trays. In like manner a space 27 is formed between end trays 21 and solid end wall 11 by the upturned metal from scored openings 13. Water for operating the device may be obtained through supply pipe 28, having conveniently placed faucet 29 and cut-off valve 30. The horizontal branch of 100 105 110

said pipe 28 is provided with pipe T's and elbow 31 for nozzle connections, each of said sprays having individual cut-off valves 32. The very fine mist or vapor given off by the 5 sprays will act more as a humidifier and very little moisture will form in drops but such as does form will collect in drain pan 8. The principal purpose of said pan 8 and the drain pipe 33 is to provide a receptacle and 10 outlet if it is desired to attach a hose to faucet 29 and wash such vegetables as onions and radishes in trays 21 positioned in said pan 8. The said drain pipe 33 is provided with trap 34. A connecting pipe between 15 inlet supply pipe 28 and drain pipe 33 is provided with valve 35. When valve 30 on supply pipe 28 is closed and valve 35 is opened drain 33 can be automatically and quickly flushed out and cleaned. Intermediate 20 faucet 29 and valve 30 on pipe 28 I provide a three part union 36 with two gaskets 37 between which is a very fine wire gauze strainer 38. This insures a clean supply 25 of water for the very fine jet issuing from nozzle 39. Said jet is directed upwardly through an opening 41 in a shallow drip pan 40, said opening 41 being surrounded by an upstanding collar 41^a. The said fine water jet after passing upwardly 30 through said opening 41 in drip pan 40 is directed at an inverted pan deflector 42 where said jet impinges against a central downwardly projecting shallow spherical segment 43 and forms a very fine mist, vapor 35 or spray, which humidifies the air surrounding the articles on display on rack 1. Any water from the jet which may form into drops is carried by capillary attraction over the spherical segment 43, the bottom of pan 42 and down the frusto-conical edge 44 of 40 said pan 42 where the water by gravity drops down into drip pan 40 and is drained out in the shallow channel 47 of said pan 40 into drain tube 45 as indicated by the arrow in Fig. 5, said tube 45 finally emptying into 45 outlet drain tube 45^a and thence to drain pipe 33. The said tube 45 passes through pan 40 and the center of its upwardly extending end 46 supports deflector pan 42 at one edge of said pan. Although the said 50 pans 40 and 42 may be of different diameters by this arrangement the centers of both pans are on the same vertical line and are in perfect alignment for operation of the fine jet as described. As can best be seen in Fig. 1 55 the spray is formed at the top of rack 1, under solid shelf 17 at a point where the cloud of mist, assisted by said shelf, spreads outwardly and downwardly through shelf 15 and trays 21 and entirely envelops the articles supported by said shelf 15 and trays 21.

Having thus described my invention what is claimed and desired to be secured by Letters Patent is:

In a device of the class described, a drain pipe or tube, a shallow dish pan supported thereby and having communication therewith, said pan having an opening in its bottom, a supply pipe disposed beneath said 65 opening and pan and in line with the opening, and an inverted pan deflector supported by said pipe above said shallow dish pan and having a central depending spherical segment in vertical alignment with the opening in said first named pan as and for the purpose specified.

WILLIAM M. WHITE
